UNITED STATES PATENT OFFICE

117,992

DESIGN FOR A LIGHT INDICATOR FOR
HEADLIGHTS

William H. Johnsen, Dallas, Tex.

Application May 6, 1939, Serial No. 84,851

Term of patent 7 years

To all whom it may concern:

Be it known that I, William H. Johnsen, a citizen of the United States of America and resident of the city of Dallas, county of Dallas, and State of Texas, have invented a new, original, and ornamental Design for a Light Indicator for Headlights, of which the following is a specification, reference being had to the accompanying drawing, forming a part thereof.

Figure 1 is a front elevational view of the light indicator for headlights embodying my new

design, the same being shown in association with an automobile headlight, indicated in dot-and-dash lines.

Fig. 2 is an edge view thereof.

Fig. 3 is a top plan view.

I claim:

The ornamental design for a light indicator for headlights, substantially as shown and described.

WM. H. JOHNSEN.
